PORTABLE ALTAR CONSTRUCTION

Emanuel I. Cohen, Philadelphia, Pa.

Application December 23, 1947, Serial No. 793,543

2 Claims. (Cl. 312—33)

1

This invention relates to improvements in altar constructions and more particularly to a portable, foldable and collapsible altar which is foldable and collapsible to a greater extent than altars extant at the present time. This invention is a continuation-in-part of my pending application Serial No. 753,563, filed June 9, 1947, now Patent No. 2,522,210.

In my prior application, the altar comprised a front wall, with folding side walls, table and retable. It has been found desirable to reduce the size of the folded altar to even a greater extent than was taught in the foregoing application, and such is accomplished in a novel manner in the present invention, in which the front wall of the altar is formed into foldable sections without detracting from its ornamental and dignified appearance.

For a more complete disclosure of the objects, construction and operation of this invention, reference is made to the accompanying specification and drawings which are descriptive and illustrative of a preferred form thereof, and in which

Figure 1 is a perspective view of the altar as set up for worship.

Figure 2 is a vertical sectional view along the line 2—2 of Figure 1, showing the corner brace and hinge for the foldable front wall.

Figure 3 is a horizontal sectional view along line 3—3 of Figure 1, showing, in dotted lines, how the front and side walls are folded.

Figure 4 is a detail showing the manner of collapsing the retable.

Figure 5 is an end view showing the retable collapsed and folded against the underside of the table.

The altar comprises preferably a sheet metal construction, of light weight, such as aluminum, having a front wall divided into two sections 10, 10a, and having side walls or wings 11, 11a, a table 12, and a retable generally indicated by the reference character 13. The front and side walls may be trimmed to give a panelled effect and the front wall is suitably embellished by a substantially centrally disposed panel 15 in which a crucifix 16 or other optional religious symbol may be removably positioned, as taught in my prior application.

The altar may be of a pressed sheet metal construction throughout, the parts being welded wherever possible, and may be finished in any suitable manner, a mahogany grained finish lending itself well to the structure for any use, giving it an impressive and dignified appearance which is particularly acceptable for religious purposes.

2

The side walls 11, 11a are secured to the front wall and folded as described in my pending application herein referred to and therefore such description need not be duplicated here.

The table 12 is fixed in position when the front and side walls are extended for use by means of dowel pins 25 projecting from the top of said walls, which engage corresponding sockets on the underside of the table top.

The retable 13 is a collapsible structure which is pivoted to the table 12 at the rear edge thereof by hinges 23, 23a. Said retable comprises a front and rear section 13a, 13b, respectively, hinged together at 13a' and 13b' by a top section 13c. The three sections are rigidly joined together, when erected, by end walls or flaps 13d and 13e, which are hinged to the ends of the front wall 13a, and fold inwardly with respect to said wall when collapsed, as best shown in Figure 4.

When erected for use, the front and end walls of the retable are held in position against displacement outwardly by means of a short downwardly projecting skirt 22 which extends around the front and end walls of the top section 13c and is bent downwardly therefrom.

The front wall sections 10, 10a meet substantially along the line 2—2 as shown in Figure 1 of the drawings. A corner angle 14, preferably of pressed metal construction, suitably braced by reinforcing webs 14a, extends the full length of each adjacent front wall section at their meeting edges and these corner angles are hinged together by a full length hinge member 17, as shown in Figures 2 and 3.

When it is desired to collapse the altar, the retable is swung backwards over the table 12 and the top is removed from the front and side walls. The end flaps 13d, 13e of the retable are folded under the table top as shown in Figure 4. The front and side walls of the supporting structure are then folded inwardly towards each other, the braces 30 being pivoted at 31, so as to fold for this purpose, as shown in Figure 3. Then the front wall section 10, with its infolded side wall 11 is swung inwardly on the hinge 17 to assume the position shown in dotted lines in Figure 3.

As shown in Figure 3, the hinge 17 lies substantially opposite the hinge points 21, 21a (only one being shown), and when the structure is folded or collapsed, the side walls are folded inwardly against their respective front sections, and then the front sections are swung about pivot 17 against one another, so that when completely folded, the front sections and side walls lie substantially parallel to one another, thus forming

a compact, substantially flat package for ease of handling and portage.

Pockets 20, to accommodate religious books, sacraments, or other paraphernalia of the profession, may be provided on the inner side walls. These may be of perforated sheet metal construction to lighten the weight thereof, or may be of any other suitable material or construction and, as shown, do not interfere with the collapsible feature of the altar.

When erected for use, the crucifix or other emblem which may be bolted to the front, one-half on each section thereof, serves to maintain said front wall sections fixed in alignment and prevents accidental shifting of either section about pivot 17, or with respect to one another. The placing of the table with the dowels engaging their corresponding sockets lends further rigidity to the structure.

It will be understood that changes in the design and construction of the invention may be made without departing from the spirit thereof as defined in the appended claims.

I claim:

1. A portable, collapsible altar comprising a front wall consisting of two sections joined at their meeting edges by hinge means, the rotational axis of said hinge means being spaced a predetermined distance from the plane of said sections, each of said sections having a free edge, a respective side wall pivotally joined at said free edge of each section on an axis spaced from the plane of said section a predetermined distance

substantially equal to said first predetermined distance, and compartment means carried by each of said side walls and having a depth less than said predetermined distance whereby said compartment means may nest within respective front wall sections when said altar is folded.

2. A table top and retable combination for a portable and collapsible altar comprising a table having means for engaging the front and side

10 walls of a supporting structure, including a retable comprising a rear wall having a lower edge hinged to said table at a bottom edge thereof and pivotal through a 270° arc with respect thereto, a top wall having an edge pivoted to the top edge of said rear wall and pivotal through a 90° arc with respect thereto, a front wall pivoted to another edge of said top wall, and side walls pivoted to lateral edges of said front wall.

EMANUEL I. COHEN.
